UREA ADDUCTS OF QUATERNARY HETERO-CYCLIC-NITROGEN HALIDES

Alfred W. Weitkamp, Lansing, Ill., Jerome W. Arkis, Hammond, Ind., and George W. Flint, Flossmoor, Ill., assignors to Standard Oil Company, Chicago, Ill., a corporation of Indiana

No Drawing. Application August 31, 1953
Serial No. 377,734

10 Claims. (Cl. 260—96.5)

This invention relates to heterocyclic-nitrogen compounds. More specifically, it relates to a novel series of chemical compositions composed essentially of urea and a quaternary heterocyclic-nitrogen compound.

One object of our invention is to convert quaternary ammonium compounds of the heterocyclic-nitrogen type into a form more readily and conveniently stored, handled, measured, and applied. Another object is to convert urea into a more effectively utilizable form. Another object is to prepare a chemical combination of urea and a quaternary ammonium compound of the heterocyclic-nitrogen class having advantageous properties as a nutrient and an antibiotic when employed in plant sprays. A further object is to separate quaternary heterocyclic-nitrogen compounds into classes according to structural configuration. Other objects of our invention will be apparent from the description thereof and the appended claims.

Quaternary heterocyclic-nitrogen compounds, such as N-laurylpuridinium chloride, N-cetyl-N-methylpiperidinium bromide, and the like, are evil-smelling, pasty, or semi-crystalline masses as ordinarily prepared. In consequence, they are difficult to measure, handle, and store, and are objectionable in many applications for which they would otherwise be adapted. We have now discovered that quaternary heterocyclic-nitrogen compounds of a certain structure can be converted into odorless, free-flowing powders by reaction with urea according to methods well-known in the art to form crystalline adducts thereof. The improved physical characteristics of the said adducts permit commercial utilization of the desirable fungicidal and germicidal properties of the nitrogen compounds in applications which have heretofore not been feasible.

The urea-reactive class of nitrogen compounds employed in producing the adducts of our invention are quaternary-ammonium compounds wherein the nitrogen atom exists as part of a heterocyclic ring structure. Thus, the said compounds may be considered to be derivatives of heterocyclic amines, wherein the ring nitrogen may be unsaturated (i. e., joined in the ring with a single bond and a double bond) as in pyridine, alpha-picoline, beta-picoline, quinoline, and the like, or saturated (i. e., joined in the ring with two single bonds) as in pyrrole, pyrrolidine, pyrrolidine, piperidine, and the like. In the case of an unsaturated ring-nitrogen compound, the quaternary ammonium compound is formed in effect by attaching to the nitrogen atom a straight-chain organic radical containing at least five methylene groups, thereby satisfying all of the non-ionic valence bonds thereof. In the case of a saturated ring-nitrogen compound, a methyl group is additionally joined to the nitrogen atom in order to satisfy the fourth non-ionic valence. Thus, our urea adducts are formed from quaternary-ammonium compounds wherein the nitrogen atom exists as part of a heterocyclic ring, and wherein the nitrogen atom is further joined to a straight-chain organic radical containing at least five methylene groups, and wherein any otherwise unattached non-ionic valence bond of the

nitrogen atom is joined to a methyl group. The straight-chain attachment for the nitrogen atom should contain at least 5 methylene groups, and may suitably be n-alkyl, n-alkenyl, n-alkynyl, n-alkadienyl, n-oxaalkyl

- 5 $\text{CH}_3-(\text{CH}_2)_m-\text{O}-(\text{CH}_2)_n-$
n-polyoxaalkyl, n-thiaalkyl
 $\text{CH}_3-(\text{CH}_2)_m-\text{S}-(\text{CH}_2)_n-$
- 10 n-polythiaalkyl, and the like, where m and n represent 0 or positive integers which must total at least 5. The urea-reactivity of the straight-chain compound is not destroyed by the substitution on the straight-chain radical of a hydroxyl or fluorine in any position, or by substitution thereon of other halogen, amine, or mercapto group in the omega position. The most useful group of 15 our new compositions which we have so far prepared are obtained from heterocyclic quaternary-ammonium salts containing a C_{10} — C_{20} n-alkyl group. These compounds have excellent germicidal, fungicidal, and surface-active 20 properties, which are retained and improved when the compounds are reacted with urea.

Quaternary compounds for use in our invention may conveniently be prepared according to the method of 25 Shelton et al., described in the Journal of the American Chemical Society, 68 (1946), 757. In this method, an approximately equimolar mixture of heterocyclic-nitrogen compound and an alkyl halide, for example, are heated at 60 to 130° C. for several hours, chlorides requiring 30 a longer time than bromides. The reaction product is crystallized twice from acetone and dried in vacuum at 25° C., yielding a dry, almost white solid.

The preparation of our new compositions of matter is carried out by reacting urea with a heterocyclic quaternary-ammonium compound of our defined class according to methods described in the prior art. The quaternary compound is preferably dissolved in any organic liquid, such as methanol, ethanol, n-butyl alcohol, ethylene glycol, or the like, which serves simultaneously to dissolve the quaternary compound and reduce the viscosity thereof, and to activate the urea for adduct formation. The resulting solution is contacted with urea. For complete reaction of the quaternary compound with urea, at least one mole of urea should be used for each methylene 45 group in the straight-chain organic radical attached to the nitrogen atom. When substantially pure adducts are desired containing a minimum of free urea, a smaller ratio of urea should be employed. The reaction is carried out at a temperature between about 0 and 60° C., 50 preferably between about 20 and 40° C., until adduct formation is complete, between about 0.1 and 2 hours being ordinarily required. The resulting reaction product is a slurry of the desired urea adduct in the diluent liquid. The slurry is subjected to filtration, settling and decantation, centrifugation, or the like to separate the adduct, and the adduct is washed with a quantity of cold diluent liquid to remove entrained mother liquor therefrom. The washed solid is then dried. The dry solid is the new composition of our invention, suitable without further 55 treatment for the many uses to which it is adapted.

It will be apparent that numerous variations of the above procedure may be employed for making our new compositions. The following variations are illustrative:

- (1) An excess of a quaternary-ammonium compound of the defined class is stirred at room temperature with a saturated solution of urea in a urea solvent, such as a lower aliphatic (C_1 to C_6) alcohol. The adduct that precipitates is filtered off, washed with a low-boiling solvent such as acetone or ether, and dried. The unreacted quaternary compound in the wash liquor is recycled.
- (2) Theoretical proportions of urea and the quaternary

3

compound are dissolved in a lower aliphatic alcohol, and the solution is spray-dried.

(3) A concentrated solution (for example, 50 to 75 percent by weight) of the quaternary compound in a lower aliphatic alcohol is mixed with the theoretical proportion of dried, powdered urea, the mixture is stirred until it becomes homogeneous, and the resulting slurry is dried.

(4) An unsaturated alcoholic solution of urea and a quaternary-ammonium compound of the defined class in approximately theoretical proportions is diluted with an organic liquid, such as ethyl ether, which functions as an alcohol solvent and a urea-adduct antisolvent. The precipitated adduct is filtered off and dried.

(5) A mixture of quaternary-ammonium compounds is treated with urea according to any of the foregoing methods. The resulting urea adduct contains only our defined class of urea-reactive quaternary-ammonium compounds. These procedures therefore afford a method for separating the said classes of quaternary-ammonium compounds from other types.

Our invention will be more fully understood from the following specific examples:

Example 1

A solution of three grams of commercial-grade N-laurylpyridinium chloride in five milliliters of methanol was rapidly mixed at room temperature with a saturated solution of 10 grams of urea in methanol. A precipitate began to form within a few minutes, and after 0.5 hour it was separated by filtration and washed on the filter funnel with ethyl ether. On being dried, the product was found to be a fine, white, odorless powder which assayed 3.59 percent by weight of chlorine, corresponding to 28 percent by weight of N-laurylpyridinium chloride in the complex or about 12 moles of urea per mole of quaternary compound. The odoriferous impurities from the original commercial-grade material were found in the filtrate.

Example 2

A mixture of three grams of N-n-octadecylpyridinium bromide, 10 grams of urea, and 50 milliliters of methanol was stirred and warmed to obtain complete solution, then cooled to room temperature for about an hour. The resulting slurry was filtered, and the solid was washed with a little ether and dried. The dry product weighed 8.3 grams and contained 5.4 percent by weight of bromine, compared with a theoretical bromine content of 19.4 percent by weight in the original quaternary compound.

Example 3

A mixture of 1.5 grams of N-cetyl-alpha-picolinium bromide, 5.0 grams of urea, and 25 ml. of methanol was reacted as described in Example 2. The dry product weighed 3.8 grams and contained 6.46 percent by weight of bromine, compared with 20 percent by weight of bromine in the original quaternary compound.

Example 4

A mixture of 1.5 grams of N-myristyl-beta-picolinium chloride, 5.0 grams of urea, and 25 milliliters of methanol was reacted as described in Example 2. The dry product weighed 3.5 grams and contained 2.50 percent by weight of chlorine, compared with 11.4 percent by weight of chlorine theoretically present in the original quaternary compound.

Example 5

A mixture of 1.0 gram of N-cetylquinolinium bromide, 3.3 grams of urea, and 17 milliliters of methanol was reacted as described in Example 2. The dry product weighed 2.1 grams and contained 4.82 percent by weight of bromine, compared with 18.4 percent by weight of bromine theoretically present in the original quaternary compound.

4

Example 6

A solution containing 10 grams of N-cetyl-N-methyl-piperidinium bromide in 50 milliliters of methanol was commingled at room temperature with a solution of 30 grams of urea in 150 milliliters of methanol, and the mixture was allowed to stand. Crystals began forming at once, and the reaction appeared to be complete at the end of one hour. The crystals were then filtered off, washed with ethyl ether, and dried in a vacuum. The dry product weighed 10 grams and contained 6.08 percent by weight of bromine, compared with 18.5 percent by weight of bromine theoretically present in the original quaternary compound. In view of the reaction procedure employed, it was obvious that the crystals could not be either urea or quaternary compound alone, and the halogen analysis indicated that the crystalline adduct contained approximately 3 parts by weight of urea per part of quaternary compound.

Our new products have outstanding advantages in many uses. They are non-hygroscopic, free-flowing talc-like powders which are easily packaged, measured, blended, and dissolved. They retain their free-flowing, powdery character in storage and under conditions of high humidity.

They are readily produced in constant and unvarying composition, and can therefore be standardized on a potency basis. They may be readily combined with other ingredients in dusting powders, in aqueous solutions, or in emulsions. The urea, being non-ionic, does not interfere with the characteristic properties of the heterocyclic quaternary ammonium compound employed, such as surface activity, or fungicidal or germicidal activity. Surface-active quaternary compounds reduce the surface tension of aqueous solutions of the adduct, and facilitate spreading and penetration of the urea in certain applications. All of these advantages represent striking improvements over the heterocyclic quaternary ammonium compounds of the prior art.

Our new compositions are useful in a wide range of applications. They may be used as a combination plant food and fungicide for fruit trees and plants in general. For this purpose, they can be conveniently used as a dust, owing to the fact that they are free-flowing, non-hygroscopic powders; and they can conveniently be combined with insecticidal agents and inert materials which are commonly applied separately. Since garden crops or ornamental plants are commonly dusted in the morning when the plants are wet with dew, the use of our new compositions or materials comprised thereof at such times is definitely advantageous, permitting rapid decomposition of the urea adduct and immediate feeding and fungicidal activity by the urea and the quaternary compound. Alternatively, our new compositions can be used advantageously as a component of sprays for plants and trees. In this connection, it is highly advantageous to employ adducts of quaternary compounds having surface-active characteristics. When such an adduct is added to water, it decomposes, yielding a solution which has a lower surface tension than a comparable urea solution, and for this reason it is more capable and efficient in feeding nitrogen to plants. If a higher ratio of urea is desired, an additional quantity of urea can be blended with the adduct, owing to the powdery form of the latter. Our new compositions are also useful in pharmaceutical preparations, for example in mouthwashes, tooth pastes, and the like, where the fluoride salts of the quaternary ammonium compound may advantageously be employed. They are especially useful in tooth powders, where their non-hygroscopic nature meets an essential qualification, and where their combined germicidal and ammonia-producing actions are highly desirable. Many other uses will be apparent to those skilled in the art.

While we have described our invention with reference to certain specific embodiments thereof, it should be understood that such embodiments are illustrative only and

not by way of limitation. Various modifications of our invention and alternative charging stocks, operating procedures, and conditions will be apparent from the foregoing description to those skilled in the art.

In accordance with the foregoing description, we claim as our invention:

1. An adduct of urea and a heterocyclic quaternary-ammonium halide wherein the nitrogen atom exists as part of a heterocyclic ring, and wherein the nitrogen atom is further joined to an unsubstituted straight-chain organic radical containing at least five methylene groups, and wherein any otherwise unattached non-ionic valence bond of the nitrogen atom is joined to a methyl group.

2. An adduct of urea and a heterocyclic quaternary-ammonium halide wherein the nitrogen atom exists as part of a heterocyclic ring, and wherein the nitrogen atom is further joined to a C_{10} - C_{20} straight-chain aliphatic radical, and wherein any otherwise unattached non-ionic valence bond of the nitrogen atom is joined to a methyl group.

3. An adduct of urea and a quaternary-ammonium halide wherein the nitrogen atom exists as part of a heterocyclic ring, and wherein the nitrogen atom is further joined to an n-alkyl radical containing at least six carbon atoms, and wherein any otherwise unattached non-ionic valence bond of the nitrogen atom is joined to a methyl group.

4. An adduct of urea and a quaternary-ammonium chloride wherein the nitrogen atom exists as part of a heterocyclic ring, and wherein the nitrogen atom is fur-

ther joined to a C_{10} - C_{20} n-alkyl radical, and wherein any otherwise unattached non-ionic valence bond of the nitrogen atom is joined to a methyl group.

5. An adduct of urea and a quaternary-ammonium bromide wherein the nitrogen atom exists as a part of a heterocyclic ring, and wherein the nitrogen atom is further joined to a C_{10} - C_{20} n-alkyl radical, and wherein any otherwise unattached non-ionic valence bond of the nitrogen atom is joined to a methyl group.

10 6. An adduct of urea and N-laurylpyridinium chloride.

7. An adduct of urea and N-n-octadecylpyridinium

bromide.

8. An adduct of urea and an N-cetylpicolinium halide.

9. An adduct of urea and N-cetylquinolinium bromide.

10 10. An adduct of urea and N-cetyl-N-methylpiperidini-

um bromide.
